SAFETY RAZOR AND BLADE THEREFOR

Edmund Jorgensen, Chicago, Ill., assignor of
one-half to Harold W. Hawes, Chicago, Ill.Application January 6, 1932, Serial No. 585,102
Renewed November 26, 1935

15 Claims. (Cl. 38—58)

This invention relates to razors and more particularly to a razor of the type commonly referred to in the industry as a safety razor.

Still more specifically the present invention relates to a razor blade holder as well as to the razor blade for use therein.

It is obvious that the only part of a razor blade which is effective for shaving is its cutting edge. In the ordinary removable razor blade of the type used in a safety holder, the material above and beyond that required for the cutting edge serves the sole function of securing the blade in its holder. The material required for the cutting edge is only a minute part of that required for the entire blade.

The material used for the entire blade is normally of uniform grade and quality and, as is well known, razor blade steel is comparatively costly to produce. Thus as to a very substantial part 20 of the cost of the ordinary safety razor blade, viz., the cost of material—the bulk of the material cost is a waste item, the greatest proportion of this high quality razor blade steel being used simply for the purpose of securing or attaching 25 the blade in its holder.

It is an object of this invention to eliminate this material waste factor by providing a removable razor blade unit for use in a holder in its entirety comprising a blade proper of such extremely narrow width that its cutting edge would necessarily be contacted in ordinary manual handling if it were not suitably protected, and so fragile that the blade would unavoidably be bent and twisted with such handling unless suitable 35 external reinforcement were provided and a scabbard for sheathing and reinforcing said blade proper.

It is apparent that manually handling such a blade without means for suitably guarding its cutting edge and reinforcing the blade, would not only be dangerous to the person handling it due to the difficulty in avoiding contacting its edge, but would be ruinous to the blade since it 40 would so easily bend and twist and as is well known, a razor blade edge is also spoiled by contacting foreign objects. This blade, without suitable protection for its cutting edge, would be difficult to manually apply to and remove from a 45 holder therefor. While it is true that all safety razor blades are in varying degrees unsafe to manually handle and the cutting edges of such blades would just as readily be spoiled by contacting foreign objects—what is very desirable with 50 other blades becomes imperative with my blade,

i. e., a suitable guard for the razor blade cutting edge must be provided.

It is, therefore, another object of my invention to provide a casing, sheath or scabbard for protectively enclosing the cutting edge of a razor blade and to serve as well as a reinforcement against bending or twisting while manually handling the blades.

It is at present well known that the ordinary safety razor blade constitutes a distinct nuisance once it has been used and discarded inasmuch as anyone is apt to cut himself on the discarded blade. Furthermore due to the fact that the cutting edge of the blade is constantly exposed once it has been removed from the paper package in which it is enclosed, it constitutes a constant source of danger inasmuch as it is always apt to cut a person who may come into contact with its cutting edge. It will, therefore, be readily understood that the so-called safety razor blade is in reality not a safe instrument at all when the same is exposed and in circulation inasmuch as its cutting edge is at all times available for cutting.

It is an object of this invention to provide a safety razor blade of such construction and arrangement that once the blade is in circulation, that is to say, when the blade is not in actual use in the holder it is 100% safe inasmuch as its cutting edge is covered and cannot possibly come into contact with the hands of the person handling the same.

Now, of course, it will be appreciated that by normally covering the cutting edge of the blade, not only is the accident hazard reduced to a practicable minimum but in addition thereto, the cutting edge is at all times protected against coming into contact with anything which would tend to damage the edge and thus reduce its effectiveness as a shaving edge. This feature is decidedly advantageous since it prolongs the longevity 40 of the blade and preserves it in the condition in which it is intended for use.

It also follows that with a blade of the type I have invented it becomes necessary to provide a new type of holder in which the blade may be inserted, which holder is of such a character as to render available the normally covered cutting edge for shaving. That is to say, a relative movement must be created between the blade and its cover so as to expose the shaving edge for use during the shaving operation. To this end I have also provided a holder for effecting the objects of my invention.

In addition to the material saving, safety and

simplicity features of my razor blade, it also has decided advantages from a manufacturing standpoint in that it may be manufactured and placed on the market with much less expense than any of the existing safety razor blades. In other words, it is cheaper to manufacture, cheaper to package and cheaper to handle and distribute to the trade.

The blade of my invention is cheaper to make not only for the reason that it has far less material than any existing blade but also due to the fact that there are fewer operations required in its construction, as for instance, the fact that there are no perforations necessary to be made in my blade for the purpose of securing it in the holder.

It is cheaper to place in package form due to the fact that it does not require any paper package to enclose it, inasmuch as the sheath or scabbard of the blade itself constitutes the package for the blade. The sheath which I have provided for normally covering the cutting edge of the blade is as will be readily appreciated, far more effective as a protective cover for the cutting edge than any paper enclosure for the blade could possibly be. However, despite the fact that the sheath is more substantial than the present paper cover, its application to the blade of my invention does not in the least increase the cost of packaging since it may be applied to the blade with greater facility than a paper cover and its cost of application to the blade is much less than the cost of the application of the typical paper wrapper now employed to cover the existing forms of safety razor blades.

Another very important advantage of this invention resides in the fact that with the sheath which I have provided for the blade the blade may be put into use with far greater facility than existing blades, for it is not first necessary to remove the blade of my invention from the paper wrapping before the blade can be applied to the razor blade holder. Not only is my razor blade unit easier to place in the holder and remove therefrom, but due to the edge thereof being at all times covered prior both to its securement in the holder and after its removal therefrom, it is much safer to handle than the existing blade which is very apt to cut the hands of the user in its application to and removal from the conventional razor blade holder.

From the foregoing it will now be evident the objects of my invention are severalfold. In the first place, it is the aim of this invention to provide a practical means for using blade which is of such small size, such narrow width and simple construction, that it may be manufactured at a far less cost than the existing blades. Another object of the invention is to provide an improved and simplified blade which has its cutting edge at all times covered, except when the blade is actually in the holder in shaving position so that the accident hazards due to cutting are reduced to a minimum. Still another object of the invention is to provide a sheath for the blade which takes the place of the ordinary paper wrapper and which may be applied to the blades for much less cost than a paper wrapper can be applied to the conventional blade. A further object of the invention has to do with the provision of a sheath for the blade which, in addition to performing its function of constituting a cover and wrapper for the blade, also serves to at all times hold the blade in a position in which it may be readily placed into an effective

shaving position within the holder. Another and further object of the invention has to do with the feature of providing a sheath and scabbard for the blade of such a character that it is at all times held in the proper position on the blade as a result of the tight fit existing between the blade and the sheath. This is an especially advantageous feature from the standpoint of economy in manufacture and from the standpoint of the ease with which the blade may be put into use. Last, but not least, it is an aim of this invention to provide a holder which is especially adapted for use with a razor blade of my invention and which is capable of causing a relative movement between the blade and its sheath so as to dispose the cutting edge of the blade in a position wherein it may be effective for shaving.

Other objects or advantages of this invention will more fully appear from the following detailed description taken in connection with the accompanying drawing which illustrates a single embodiment thereof and in which:

Figure 1 is a side view of a razor holder with the blade of my invention therein;

Figure 2 is a plan view of the razor construction shown in Figure 1;

Figure 3 is a perspective view of a safety razor blade unit embodying the features of this invention;

Figure 4 is an enlarged cross-sectional view taken through the head of the razor blade holder and more particularly on the line IV-IV of Figure 1 looking downwardly;

Figure 5 is an enlarged fragmentary sectional view partly in elevation taken on the line V-V of Figure 2 looking in the direction indicated by the arrows and showing the razor in its closed position with the blade edge exposed for shaving;

Figure 6 is a view similar to Figure 5 taken on the line VI-VI of Figure 2 but differing from Figure 5 in that it shows the razor in its open position;

Figure 7 is also an enlarged sectional view similar to Figures 5 and 6 taken on the line VII-VII of Figure 2 looking in the direction indicated by the arrows and illustrating more in detail the mechanism employed for causing relative movement between the blade and its sheath; and

Figure 8 is a transverse sectional view taken on the line VIII-VIII of Figure 3 looking in the direction indicated by the arrows and showing the position of the cutting edge of the blade when the cutting edge is exposed for the shaving operation, it being, of course, appreciated that this cutting edge is not exposed during the normal handling of the blade but is only exposed in the manipulation of the holder to cause a relative movement between the blade and the sheath whereby the cutting edge of the blade is placed in an effective cutting position.

As shown on the drawing

The reference character 10 designates generally the handle of my razor blade holder which handle may be of any desired or suitable construction. This handle has secured to one end a head designated by the reference character 11 which is so constructed as to be adapted to receive a razor blade unit embodying the features of this invention.

The head, 11, embodies a U-shaped construction which includes downwardly disposed arms, 13 and 14, connected by a cross-piece, 15, (Fig. 4). This construction, 12, is rigidly secured to the handle, 10, and constitutes the supporting struc-

ture or foundation for the movable parts of the razor blade holder. The arms, 13 and 14, of this head are downwardly inclined as will be noticed in Figures 5 and 6 so that these arms are disposed at an angle to the longitudinal axis of the handle, 10.

Secured to the cross member, 15, of the U-shaped construction, 12, is a combination mounting member and guard strip, 16, (Figures 4, 5 and 6) which forms integral with its lowermost edge the usual guard piece, 17, between the teeth of which the shaving soap is adapted to pass during the shaving operation. This mounting member, 16, has a pair of spaced apertures, 18, (Fig. 4) for cooperation with the projections, 19, on the sheath, 20, of my razor blade unit designated generally by the reference character 22, which unit is adapted to be seated on the mounting member 16, as shown in Fig. 4 with the projections engaged, 19, in the aperture, 18. These apertures, 18, cooperate with sheath, 20, to fully align the razor blade unit with the holder and to hold the razor blade unit against lateral displacement on the mounting member, 16.

As shown in Figures 3 and 8 the blade unit 22 embodies the relatively narrow U-shaped scabbard or sheath 20 provided with the projections 19, and in which scabbard or sheath is disposed a relatively narrow razor blade 23 having a cutting edge 24. This razor blade and its cutting edge 24 is adapted to be normally housed within the sheath 20 as shown in Figure 3, so that the cutting edge 24 is covered and cannot be damaged and can not come into contact with the hand so as to cut or otherwise hurt the person in handling the blade. The ends of this blade 23 project beyond the ends of the relatively narrow sheath 20, as indicated by the numeral 25 in Fig. 3. These free ends 25—25 are adapted to be engaged by the arms in my razor blade holder to cause a relative movement between the sheath and the razor blade whereby the edge, 24, is uncovered for use during shaving and is recovered after such use and prior to removal from the holder.

It is to be noted at this time that the blade 23 is of the safety razor blade type, but different from the ordinary safety razor in that it is exceedingly narrow whereby quite a saving may be effected in the cost of the manufacture of the blade. The sheath 20 in addition to performing its function of constituting a cover for the cutting edge 24 also reinforces the blade and in reality constitutes a package or enclosure for the blade, whereby this blade unit may be sold to the trade without the additional wrapping thereon such as the paper wrapping which is at present used to cover the conventional razor blade. Furthermore, it is to be noted that I find that I can apply this sheath or casing to the razor blade with less cost than a paper wrapper can be applied to the conventional blade.

Then too, it is to be noted that the blade 23 is not in any way secured to the sheath 20 other than by the tightness of fit between the blade and the sheath. In other words, the sheath is tightly disposed on the blade so that the blade will not become accidentally displaced from the sheath and thus expose the cutting edge of the blade during the handling of the blade unit 22. The sheath may be made of any suitable material such for example as metallic sheet, fiber sheet and the like. Its only prerequisite is that it be relatively rigid so that it will properly enclose

and reinforce the blade and cover the edge 24 of the blade as shown in Fig. 3.

When this blade unit 22, shown in Fig. 3, is placed in this holder, as shown in Fig. 4, the free ends 25 of the blade unit are engaged by the forked ends 26 and 28 of a pair of spaced arms 29 and 30 disposed outside of the arms 13 and 14. These arms are loosely and pivotally mounted upon pivots or studs 31 and 32 having threaded portions 33 and 34 threadingly connected to the spaced arms 13 and 14 and to a pair of caps 35 and 36 disposed on the inside of the holder. Also these pivot studs 31 and 32 have enlarged shank portions 37 and 38 about which the arms 29 and 30 are adapted to pivot as well as a pair of auxiliary arms 39 and 40 disposed on the outer sides of the arms 29 and 30.

The two arms 29 and 30 constitute the blade engaging arms and the two arms 39 and 40 constitute the arms for manually actuating the arms 29 and 30 to project the cutting edge 24 out of the sheath 20 of the razor blade unit 22.

The two outer arms 39 and 40 are connected by an outer cross-piece 41 including a laterally and inwardly extending blade unit engaging member 42 (Figs. 5, 6 and 7). This member 42 when the razor holder is in an open position is disposed in the position shown in Figs. 6 and 7, and when the razor holder is in a closed position it is disposed in the position shown, Fig. 5, in which latter position it is disposed on top of the razor blade unit 22.

In this position it will be observed that the razor blade unit has its cutting edge 24 (Fig. 5) projected to an exposed position directly over the guard teeth 17. On the other hand when the razor is open the blade edge is retracted within the sheath and the member 42 is drawn away from the sheath so that the blade unit may be removed from the top of the supporting member 40.

I shall now proceed to describe in detail the connecting means between the arms 39—40 and the arms 29—30 whereby the first-mentioned set of arms are enabled to actuate and move the second mentioned arms to project and retract the blade relative to the sheath. Since the means between the arm 39 and its associated arm 29 is identical to the means between the arm 40 and its associated arms 30, it is thought that a description of the means in connection with the first-mentioned arms will be sufficient for both sets of arms.

Referring to Figs. 5, 6 and 7, it will be observed that the cross-piece 41 of the arm 39 is adapted to engage a shoulder 43 on the arm 29 upon manual movement or rotation of the arms 39 and 40 and the cross-piece 41 about the axis of the associated pivot pins 31 and 32. A practically idle movement is permitted between the cross-piece 41 and the shoulder 43 before the cross-piece 41 is permitted to come into contact with the shoulder whereby the front member 42 of the arms 39—40 is permitted to overlap the razor blade unit 22, which is disposed on the supporting member 16 thereby enabling this cover member 42 to hold the razor blade unit on the member 16 while the razor is being closed. Once the cross-piece 41 has engaged the shoulder 43, the arms 29—30 and 39—40 are caused to move together about the axis of the pivots 31 and 32.

Now it will, of course, be appreciated that a movement of the arms 29 and 30 will result in the bifurcated or forked ends 26 and 28 of these arms projecting forward the blade 23 relative to

the sheath 20. In other words, the forked ends 26 and 28 due to their engagement with the free ends 25 and 25 of the razor blade 23 cause the razor blade as a result of forward movement of the arms to be advanced out of the sheath which is prevented from partaking in the movement by the projections 19, whereby the cutting edge of the blade is exposed for shaving.

The downward pivoting movement of the arm 10 29 is limited by the projecting ends of the guard member 17, shown in Fig. 5.

It will, of course, be appreciated that the cross-piece 41 and its integral arms 39 and 40 are actuated downwardly by manually depressing the cross-piece 41 to push it downwardly to the position shown in Fig. 5.

When it is desired to open the razor as shown in Fig. 6 the cross-piece 41 is pushed upwardly to the position shown in Fig. 6. This movement 20 may be effected by the operator of the razor putting his thumb on the under side of the cross-piece to push it upwardly. As this cross-piece 41 and its arms 39 and 40 are moving upwardly a lateral extension or flange 51 on the under side 25 of each of the arms 39-40 comes into engagement with the under edge of the corresponding arms 29-30 whereby these arms are raised upwardly or, in other words, are pivoted about the axis of the pivots 31 and 32 along with the cross-piece 41 and the arms 39 and 40. In other words, the upward movement of the piece 41 also results in the upward movement of the two arms 29 and 30 whereby these arms through their bifurcated ends are enabled to retract the razor blade 35 inside of its sheath so that the cutting edge 24 of the razor blade is covered by the sheath and is no longer exposed as shown in Fig. 6. The upward movement of the arms 29-30 is limited by the stop 50 formed integral with the arms 13-14. 40 Once the cross-piece 41 and its integral arms 39 and 40 have been raised to the open position as shown in Fig. 6, the razor blade unit 22 may thereafter be removed from the top of the supporting member 16 and discarded. This discarded 45 blade, due to the fact that its cutting edge is completely covered will not in any way injure or cut the hands of anybody who may happen to handle the discarded blade.

Inasmuch as the object and advantages of this 50 invention have been covered and fully described in the fore part of the present specifications, it is not thought to be necessary to further elaborate on the same. Of course, it is to be understood that although I have illustrated and described in 55 detail the preferred embodiment of the invention, the invention is not to be thus limited but only so far as defined by the scope and spirit of the appended claims.

I claim as my invention:

60 1. As an article of manufacture, a blade having a cutting edge and an enclosure for the blade cutting edge comprising spaced sheet portions between which the blade is disposed with its cutting edge in proximity to an open end of the enclosure ready to be projected through said open end into an exposed position, said blade being longer than said enclosure so as to have its ends project beyond the ends of the enclosure for engagement with parts of a blade holder.

65 70 2. The combination with a razor blade having a cutting edge confined within a scabbard and provided with free ends of a holder for the blade having means for projecting the blade edge out of the scabbard into a shaving position, said means including arms for engaging said free ends

of said blade to cause a relative movement between the blade and its scabbard.

3. The combination with a razor blade having a cutting edge confined within a scabbard and provided with free ends of a holder for the blade edge out of the scabbard into a shaving position, said means including arms for engaging said free ends of said blade to cause a relative movement between the blade and its scabbard upon closing 10 and opening of the razor blade holder.

4. The combination with a razor blade having a cutting edge confined within a scabbard, of a holder for the blade having means for projecting the blade edge out of the scabbard into a 15 shaving position, and for thereafter retracting the edge back into the confines of the scabbard prior to removal of the blade from the holder, said means in engagement with said blade for causing relative movement between the blade 20 and its scabbard each time the holder is closed and opened.

5. The combination with a safety razor blade unit having a cutting edge confined within a scabbard, of a holder for the blade having means 25 for projecting the blade edge out of the scabbard into a shaving position, said blade and scabbard being in tight frictional cooperation with each other both while in and out of said holder.

6. As an article of manufacture, a safety razor 30 blade unit for use in its entirety in a holder, insertable in and detachable from the holder in its entirety, comprising a blade proper having a cutting edge adapted to be disposed for shaving when the blade unit is in the holder, said 35 blade proper being of such narrow width and thinness that the cutting edge would necessarily be contacted in the normal ready manual handling of the blade proper unless protected by a guard therefor and so flexible as to require reinforcement to permit such handling without bending or deforming said blade proper, and a scabbard therefor sheathing said cutting edge and reinforcing said blade proper so as to permit such manual handling.

7. As an article of manufacture, a holder for 45 a safety razor blade unit comprising relatively movable parts and having a cutting edge, for use in its entirety in the holder, said holder including a handle and a support for the razor 50 blade unit and means for causing relative movement between the parts of said blade unit to dispose the cutting edge of said blade unit in proper shaving position.

8. As an article of manufacture, a holder for 55 a safety razor blade unit comprising relatively movable parts and having a cutting edge, for use in its entirety in the holder, said holder including a handle and a support for the razor 60 blade unit and means for causing relative movement between the parts of said blade unit to dispose the cutting edge of said blade unit in proper shaving position, said movement being effected by the act of securing the blade unit to said support.

9. As an article of manufacture, a holder for 70 a safety razor blade unit comprising relatively movable parts and having a cutting edge, for use in its entirety in the holder, said holder including a handle and a support for the razor 75 blade unit and means for causing relative movement between the parts of said blade unit to dispose the cutting edge of said blade unit in proper shaving position, and also having means for acting on said blade unit prior to its release

from the holder to cause one of the blade unit parts to sheath said cutting edge.

10. The combination with a razor blade unit comprising a blade proper having a cutting edge adapted to be disposed for shaving when the blade unit is in a holder and a scabbard therefore relatively movable with regard to said blade proper, for use in its entirety in a holder, insertable in and detachable from the holder in 10 its entirety, of a holder for said blade unit with means for causing relative movement between the cutting edge of the blade proper and the scabbard.

11. A safety razor blade unit comprising a sheath, a portion having a cutting edge disposed 15 within the sheath, the sheath and portion being relatively movable to expose or cover the cutting edge, the portion having means fixed thereto, and exposed externally of the sheath for shifting the sheath and portion relatively.

20 12. A safety razor blade unit comprising a sheath, a portion having a cutting edge disposed within the sheath, the sheath and portion being relatively movable to expose or cover the cutting edge, the blade unit having means for cooperating 25 with a holder adapted to shift the sheath and portion relatively.

13. A safety razor blade unit comprising a sheath, a portion having a cutting edge disposed within the sheath, the sheath and portion being relatively movable to expose the cutting edge, the blade unit having means for cooperating with 5 a holder adapted to shift the sheath and portion relatively.

14. A safety razor blade unit comprising a sheath, a portion having a cutting edge disposed within the sheath, the sheath and portion being 10 relatively movable to expose or cover the cutting edge and means accessible from the exterior of the blade unit for shifting the sheath and portion relatively, and for securing the blade unit in a holder therefor.

15. A safety razor blade unit comprising a sheath, a portion having a cutting edge disposed within the sheath, the sheath and portion being relatively movable to expose or cover the cutting edge, said sheath and portion being arranged 20 to be relatively moved without requiring their separation at any time, and having means for securing the blade unit in a holder therefor.

EDMUND JORGENSEN. 25
